REVERSIBLE GARMENT HANGER

John G. Warmath III, Brooklyn, N.Y., assignor to Yankee Plastic, Inc., New York, N.Y., a corporation of New York

Filed Feb. 12, 1962, Ser. No. 68,784

Term of patent 3½ years

(Cl. D80—8)

FIG. 1

FIG. 2

FIG. 3

FIG. 4

FIG. 5

FIG. 1 is a front elevational view of a reversible garment hanger, showing my new design, and

FIG. 2 is a side elevational view,

FIG. 3 is an enlarged cross-section of FIG. 1 taken along lines 3—3,

FIG. 4 is an enlarged cross-sectional view of FIG. 1 taken along lines 4—4,

FIG. 5 is an enlarged cross-sectional view of FIG. 1 taken along lines 5—5, and

FIG. 6 is an enlarged fragmentary rear elevational view thereof taken in rectangular area 6 of FIG. 1.

I claim:

The ornamental design for a reversible garment hanger, substantially as shown.
